UNITED STATES PATENT OFFICE

JOHN McCARTHY, OF HOLLYWOOD, CALIFORNIA

DESIGN FOR AN OVEN

Application filed March 24, 1930. Serial No. 35,013. Term of patent 14 years.

To all whom it may concern:

Be it known that I, JOHN McCARTHY, a citizen of the United States, residing at Hollywood, in the county of Los Angeles and State of California, have invented a new, original, and ornamental Design for an Oven, of which the following is a specification, reference being had to the accompanying drawings, forming a part thereof.

Fig. 2, is a front elevation thereof.

I claim:

The ornamental design for an oven as shown.

Signed at Los Angeles, in the county of Los Angeles, and State of California, this 19 day of March, 1930.

JOHN McCARTHY.
